CLAIM

The ornamental design for an electrical stimulator, as shown and described.

DESCRIPTION

FIG. 1 is a top perspective view of an electrical stimulator showing our new design;

FIG. 2 is a bottom perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

The broken lines in the figures are included for the purpose of illustrating portions of an electrical stimulator and form no part of the claimed design.

1 Claim, 6 Drawing Sheets(56)
